US00D859986S

(12) **United States Design Patent** (10) Patent No.: **US D859,986 S**
Marantis et al. (45) Date of Patent: **** Sep. 17, 2019**

(54) **STOPPER FOR BOTTLE**

(71) Applicant: **CORNERSTONE CM, INC.**, Poland, OH (US)

(72) Inventors: **Michael G. Marantis**, Poland, OH (US); **Richard A. Ponton**, New Milford, CT (US); **Joshua W. Hubbard**, New Milford, CT (US); **Jonathan P. Richards**, Derby, CT (US)

(73) Assignee: **Cornerstone CM, INC.**, Poland, OH (US)

(**) Term: **15 Years**

(21) Appl. No.: **29/625,282**

(22) Filed: **Nov. 8, 2017**

CLAIM

The ornamental design for a stopper for bottle, as shown and described.

DESCRIPTION

FIG. 1 is a top perspective view of a stopper for bottle, showing our new design;

FIG. 2 is a bottom perspective view thereof;

FIG. 3 is a left side view thereof, the right side being a mirror image thereof; and,

FIG. 4 is a front view thereof, the rear view being a mirror image thereof.

(Continued)

The broken lines are shown for the purpose of illustrating parts of the stopper for bottle that form no part of the claimed design.

1 Claim, 1 Drawing Sheet

Related U.S. Application Data

continuation of application No. 14/540,477, filed on Nov. 13, 2014, now Pat. No. 9,517,922, and a continuation-in-part of application No. 29/509,028, filed on Nov. 13, 2014, now Pat. No. Des. 763,691.
